[57] ABSTRACT

Container handling and transporting system in which the container is lifted onto and removed from the flat deck of a transporting vehicle by the forks of a fork lift truck and registering locating and locking devices are released by spreading movement of the forks of the fork lift truck prior to lifting the container from the flat deck of the vehicle. The locating and locking devices are in the form of domed locators and socket members registrable with the domed locators, and having latch dogs slidably guided therein and biased to have latching engagement with the domed locators. The latch dogs are biased into their latching positions and have follower members engaged by the forks of a fork lift truck and released by outward spreading movement of the forks.

CONTAINER HANDLING AND TRANSPORTING SYSTEM

FIELD OF THE INVENTION

Handling and transfer system for containers of the type classified in Class 214.

BACKGROUND, SUMMARY AND OBJECTS OF INVENTION

In my U.S. Pat. No. 3,653,521 dated Apr. 4, 1972, a system and apparatus for locating and locking freight containers on the flat decks of vehicles is disclosed. This patent shows a locking mechanism for locking the container to the deck of the vehicle in which release of the locking mechanism is through a cable by inward movement of the forks of a fork lift, or by upward movement of the forks of the fork lift. Similar locking and locating mechanisms are shown in U.S. Pats. to McHugh 2,812,974 and Loomis No. 3,014,604. The mechanisms of these patents are all relatively complicated, requiring systems of flexible cables and links and levers or links and levers by themselves, to release the containers from the decks of the vehicles, all of which lend to the complexity of the system and are subject to frequent maintenance.

The apparatus and system of the present invention provides a simple and reliable locating and locking means for locking containers to the flat decks of freight transporting vehicles in which a direct connection is provided from the forks of a fork lift to the locking means, to release the locking means by spreading movement of the forks.

An advantage of the present invention is in the simplicity and reliability of the locking and release mechanism, requiring a minimum number of parts and releasable by the simple spreading movement of the forks of the fork lift.

Another advantage of the invention is in the use of removable domes on the deck of the vehicle, registering with sockets on the bottom of the container, enabling the deck of the vehicle to be cleared for tractors or loading wheeled containers, in a simple and expeditious manner.

A further advantage in the invention is in the biasing of the latching mechanism into a locking position and the release of the mechanism by spreading movement of the forks of a fork lift, enabling the latching mechanism to be self-locking upon the lowering of a container thereon and thereby increasing the reliability and effectiveness of the locking mechanism.

A still further advantage of the invention is the arrangement of the locking mechanism to enable plural locating and locking devices to be located on opposite sides of fork openings and be simultaneously released by spreading movement of the forks of a fork lift.

A principal object of the invention, therefore, is to provide an improved system and apparatus for locating and locking freight containers to the flat decks of transporting vehicles, arranged with a view toward utmost simplicity and efficiency in construction and operation.

Other objects, features and advantages of the invention will be readily apparent from the following description of certain embodiments thereof, taken in conjunction with the accompanying drawings, although variations and modifications may be effected without

departing from the spirit and scope of the novel concepts of the disclosure.

DESCRIPTION OF THE DRAWINGS

5 FIG. 1 is a diagrammatic fragmentary top plan view of a base for lifting a container with the top plate for the base removed.

10 FIG. 2 is a longitudinal sectional view of the base taken substantially along the centers of the locking devices shown in FIG. 1, and showing the locating members mounted on the flat deck of a vehicle. FIG. 3 is a fragmentary side view of the base shown in FIGS. 1 and 2, illustrating a fork opening for the forks of a fork lift.

15 FIG. 4 is a horizontal sectional view taken through a portion of the base and showing the locking socket and latch mechanism in plan with the latch mechanism in its locked position.

20 FIG. 5 is a fragmentary plan view somewhat similar to FIG. 4 but showing the locking mechanism in its released position.

25 FIG. 6 is a sectional view taken substantially along lines VI—VI of FIG. 4, and showing a locating member extending upwardly from the deck of a transporting vehicle in full and in alignment with a locking socket.

30 FIG. 7 is a fragmentary plan view of a base showing a modified form in which my invention may be embodied; and

35 FIG. 8 is a sectional view taken substantially along line VIII—VIII of FIG. 7.

DESCRIPTION OF PREFERRED EMBODIMENTS OF INVENTION

In FIGS. 1 to 6 of the drawings, I have shown a base 35 10, which may be the base of a container 11, of a type adapted to be carried directly on a flat deck 12 of a railway flatcar, trailer, truck or ship.

40 The container 11 is fragmentarily shown in FIG. 3 and is of a generally box-like form and may be of various selected lengths and of widths coforming to or narrower than the width of a railway flatcar or trailer. Said container is only fragmentarily shown in FIG. 3 and may have a closed top and parallel side and end walls mounted on and extending upwardly from the base 10, and is of a well known form, so need not herein be shown or described further.

45 The base 10 is herein shown as being the base of a container, but may be a separate base or platform used to lift and lower a container and lock the container to the flat deck of a freight transporting vehicle. The base, therefore, is rugged and is shown as comprising parallel spaced side frame members 13, which may be channels, with the webs thereof extending along the outside of the base, and end frame members 15 connecting said side frame members together, at their opposite ends. The base also includes a plurality of parallel spaced transverse channels 16 extending between the side frame members 13 and spacing said side frame members apart and rigidifying the base structure.

50 60 65 Certain of the transverse channels 16 in alignment with one side of openings 17 in the webs of the side frame members 13 and with said openings forming fork openings for the forks 18 of a fork lift (not shown). Extending from the opposite side of the opening 17 from the channel 16 are aligned channels 19 terminating at their inner ends into gusseting channels 20 connected at their inner ends to relatively short longitudinally ex-

tending channels 21, extending from a transverse channel 16 on the opposite side of the fork opening from the first mentioned channel 16.

The channels 19, 20 and 21 define a receptacle 22 for a locking socket member 23, mounted between said channels and opening to a fork opening. The socket member 23 will hereinafter more clearly appear as this specification proceeds. The end and side frame members and transverse channels 16 are connected together by a top plate 24, which may form a bottom plate for the container, where the base is the base of a container. The bottom of the base is shown as being open.

The deck 12 of the freight transporting vehicle may be a conventional deck of a railway flatcar or trailer. Said deck 12 is diagrammatically shown as having a flat top plate 25 and the conventional end, side and center beams suitably connected together and is no part of the present invention so need not herein be shown or described in detail.

Abutting the bottom of the top plate 25 of the flat deck 12 are the flanges of flanged collars 26, centered along the longitudinal center line of the deck, and welded or otherwise secured to the bottom of said top plate 25. The collar portions of the flanged collars 26 form mountings for shanks 27 of locating and locking members 29 registerable with the sockets in the socket locating and locking members 23 and suitably retained to said collars. The locating members 29 are shown as being in the form of domes but need not necessarily be domes and may be conical, pyramidal or of any other suitable form. Each dome 29 has an outwardly opening horizontally extending locking slot 32, the inner wall of which extends across the cylindrical wall 30 in the form of a chord of the circle defined by the cylindrical wall 30. The slot 32, as shown in FIG. 6, has a top wall 33 extending horizontally and a downwardly inclined bottom wall 35 inclined downwardly from the inner end of said slot. The slot 32 is thus so formed as to be readily accessible to a latch dog 36, shown in FIG. 4 as being in the form of a blade extending across the interior wall of the socket member when the latch dog is in its latching position. The dome 29 and slot 32 thus serve as a keeper from the latch dog 36 to lock the base 10 to the vehicle, with the container 11 thereon.

The shanks 27 and the domes 29 may be detachably secured to the collars 26 in a suitable manner, or may be of such a length that they will be retained to the collars by the weight of the base and container, it being understood that the domes are solid castings or forgings and are relatively heavy, so will be retained to the deck 12 as the latch dogs are released, and the base 10 is lifted from the deck.

It should here be understood that the base 10 may be provided with any suitable number of domes determined by the number and length of the containers to be retained to the vehicle. As for example, the deck 12 may carry three 27' containers. In such a case, six domes will be provided, with two domes for each container. It may also carry two 40' aligned containers in which case four domes will be provided. Moreover, the collars 26 may be located along the deck in such a manner that the vehicle may carry two 27' containers and one 40' container or three 27' containers, where the car is 96' in length.

Referring now in particular to the socket members 23, each socket member is in the form of a collar having an interior cylindrical wall 37 with bosses 39 ex-

tending laterally of the collar in opposite directions. Said collars abut the bottom of the plate 24 and are secured to the longitudinal channels 21 as by machine screws 40, extending through the webs of the channels 21, and threaded in said collars on opposite sides of guide passageways 41 extending along said bosses. The guide passageways 41 may be drilled passageways and serve as slidable guides for rods 42, extending from opposite sides of said collars, and slidably guided therein and extending within the fork openings 17, when the latch dog 36 is in its locking position.

The latch dog 36 is in the form of a blade movable along a slot 43 in the collar or socket member 23, and extending across the interior cylindrical wall of said socket member with its inner end forming a chord with respect to the cylindrical wall 37. The blade forming the latch dog 36 is shown as formed integrally with a yoke 45, having bosses 46 extending along the rods 42 and abutting shouldered portions thereof and retained in abutting engagement therewith as by nuts 47 threaded on said rods. A follower yoke 49 having bosses 50 at its opposite ends is mounted on opposite ends of the rods 42 from the yoke 45, on said bosses 50, and is retained into engagement with shouldered portions of said rods (not shown) as by nuts 51, threaded on said rods. Biasing springs 52 encircle the rods 42 and are interposed between the bosses 39 of the socket members 23 and the bosses 50 of the follower yoke 49 to bias the latch dog 36 in the position shown in FIG. 4. The springs 52 are shown as being compression springs which should be capable of being loaded to a load of 400 lbs. each, to provide sufficient force to retain the latch dog 36 into locking engagement with the notch 32 of the dome 29. The follower yoke 49 has a follower face terminating into a peak 54 engaged by the fork 18 of a fork lift truck and moving the rods 42 and latch dog 36 against the compression springs 52, to release the latch, by spreading movement of the forks of the fork lift truck along the fork openings 17.

The blade of the latch dog 36 has a top horizontal face 55 rounded at its inner end and terminating into a downwardly inclined face 56. The face 56 engaging the hemispherical wall 31 of the dome 29 as the base 10 is lowered onto the deck 12 is cammed inwardly by said hemispherical wall 31 to come into locking engagement with the notch 32. Outward movement of the latch dog into its release position is limited by a gusset reinforcing the yoke 49, as shown in FIG. 5.

It may thus be seen that a simplified form of self-locking, latching and release means for aligning a base, which may be the base of a container on the flat deck of a freight transporting vehicle and locking the base thereto has been provided, biased into its locking position, and released by spreading movement of the forks of the fork lift truck relative to each other, prior to lifting the base by the forks of the fork lift truck.

Referring now in particular to the form of the invention illustrated in FIGS. 7 and 8, in the modified form of the invention shown in these figures, socket members 59 and 60 are provided on opposite sides of each for opening 17, to provide four aligned locking and socket members for each container, in which the latch dogs on each side of the fork openings are simultaneously released by spreading movement of the forks of a fork lift truck. In this form of the invention, the base is of the same general construction as that shown in FIGS. 1 and 2, so the same part numbers will be ap-

plied to parts common to those in the form of the invention illustrated in FIGS. 1 to 6.

The socket member 59 is like that shown in FIGS. 1 through 6, so the same reference numerals will be applied to the same parts as in FIGS. 1 through 6 and a description thereof need not be repeated herein. The rods 42 have a yoke 49a secured thereto by the nuts 51 and abutted by compression springs 52 encircling said rods, as in the form of the invention shown in FIGS. 1 through 6. The yoke 49a has a follower face 54a engaged by a fork 18 of the fork lift truck and moved into release position by lateral spreading movement of said fork.

The yoke 49a and follower face 54a form one wall of an upwardly opening channel, extending across the fork opening, and having a bottom web 61 and a flange 62 extending upwardly therefrom on the opposite side of said channel from the follower face 54a. A latch dog 63 has a vertical leg 65 extending along the outside of the flange 62 and secured thereto as by machine screws 66. The latch dog 63 is in the form of a blade and said latch dog and vertical leg 65 extend through an opening 67 in the web of the channel 16. The latch dog 63 is of the same general form as the latch dog 36 and slidably extends through a slot 69 in the wall of the locking socket 60, and has locking engagement with an associated dome 29 in the same manner the latch dog 36 has locking engagement with its dome 29.

It may here be seen that with this construction, as a fork 18 of a fork lift truck is spread to move laterally of the truck, it will engage the follower face 54a of the yoke 49a and simultaneously move the two latch dogs 36 and 63 into release positions to release the base from the flat deck of the flat car. The present latching arrangement thus provides dual protection and has the advantage of locking the base and container to four instead of two domes, projecting upwardly from the deck of the flat bed vehicle, and the two latch dogs on opposite sides of the center of the vehicle are simultaneously released, by a single spreading operation of the forks of the fork lift truck.

I claim as my invention:

1. A container handling and transporting system comprising,
a vehicle having a flat deck,
a fork lift having laterally spaced spreadable forks for lifting the container,
at least two longitudinally aligned locating and locking members projecting upwardly from said deck,
a base for removably supporting a container on said flat deck and having parallel spaced fork openings extending thereacross,
socket members carried by said base and having downwardly opening sockets registerable with said locating and locking members,
latch dogs guided in said socket members for movement in a direction longitudinally of said base and biased for interengagement with said locking and locating members, and
release means for said latch dogs for releasing said latch dogs from said locking and locating members by spreading movement of the forks of the fork lift, to accommodate the forks to lift the base upon upward lifting movement thereof, including guide members guided in each socket member along opposite sides of the socket members,

means connecting the guide members with an associated latch dog, to move said latch dog into its latching and release positions,
a yoke connecting the ends of said guide members on the opposite side of said guide members from said latch dog and extending into the fork opening, means biasing said yoke to extend into the fork opening and form a follower surface cammed by spreading movement of the fork of a fork lift truck to release said latch dog from interengagement with the associated locking and locating member.

2. The container handling and transporting apparatus of claim 1, wherein the means biasing the guide members to bias the latch dog to extend within the socket of the socket member to have interengagement with an associated locking and locating member comprise springs encircling said guide members and interposed between said socket member and said yoke.

3. The container handling and transporting system of claim 2,

wherein the latch dogs are in the form of blades slidably guided in the socket members and biased to extend within the sockets of said socket members, and

wherein the locking and locating members are in the form of domes extending upwardly of the deck of the vehicle and each having a latch opening therein forming a keeper for the associated latch dog.

4. The container handling and transporting system of claim 1,

wherein the socket members are in the form of collars having socket openings therein and bosses extending from opposite sides of said collars,

wherein the release means for the latch dogs comprise rods slidably guided in said collars, means mounting said latch dogs on said rods for movement therewith, yokes extending across the opposite ends of said rods from said latch dogs and mounted thereon, said yokes having follower faces extending into the fork openings and cammed by spreading movement of the forks of the fork lift truck to move the latch dogs out of socket openings of said collars by camming engagement of the forks of a fork lift with said follower faces of said yokes and spreading movement of said forks.

5. The container handling and transporting apparatus of claim 4,

wherein each latch dog is in the form of a blade slidably guided in the associated collar to extend across the socket opening in said collar in a chordal direction when the latch dog is in its latching position, and

wherein the means biasing said latch dogs in their latching positions comprise springs encircling said rods and interposed between said bosses and yokes.

6. The container handling and transporting system of claim 2,

wherein two aligned socket members are carried in said base on opposite sides of each fork opening, wherein locking and locating members are provided on the flat deck of the vehicle for registry with said socket members as said base is lowered onto the deck of the vehicle,

wherein connected latch dogs are slidably guided in said socket members to have latching interengag-

ment with said locking and locating members on opposite sides of the fork opening, wherein the yoke is operatively connected with each of said latch dogs and has a follower face cammed by lateral spreading movement of a single fork of a fork lift truck to simultaneously release said latch dog from interengagement with its associated locking and locating member.

7. the container handling and transporting apparatus of claim 6, wherein the yoke defines one flange of a channel-like member of a width substantially equal to the width of the fork opening, and wherein a latch dog opposite said channel-like member from said follower face slidably extends within an associated aligned collar for slidable engagement therewith.

8. In a removable container for lading and in combination with a flat deck vehicle having at least two longitudinally spaced locking and locating members projecting upwardly therefrom, having latch openings therein, and a fork lift having laterally shiftable forks lifting the container from and placing the container on the vehicle deck,

said container having a base having parallel side beams, end beams extending across said side beams at opposite ends thereof, parallel spaced transverse beams extending between said side beams, openings in said side beams opening to the spaces between certain of said transverse beams and forming fork openings for the forks of a fork lift truck, said openings being of sufficient width to accommodate spreading movement of the forks when in said fork openings, socket members in the spaces between certain of said transverse beams and having vertically extending sockets, latch dogs slidably guided in said socket members and biased to extend into the open portions thereof, yokes in said fork openings, having follower faces adapted to be engaged by the forks of a fork lift truck, operative connections between said yokes and latch dogs, moving said latch dogs into release positions out of the sockets of said socket members upon lateral spreading movement of the forks of the fork lift, to release the container from the vehicle deck by upward lifting movement of the forks, including bosses projecting from opposite sides of said socket members, guide members slidably guided in said bosses and connected with said latch dogs at one end and with said yokes at their opposite end, and

spring means interposed between said bosses and yokes and biasing said yokes to extend into said fork openings and said latches to extend into the sockets of said socket members.

9. The removable container of claim 8,

wherein the latch dogs are in the form of blades extending across the sockets of said socket members when in their locking positions and connected at their opposite ends to said guide members slidably guided along the outsides of said socket members.

10. The removable container of claim 8, wherein the socket members are in the form of collars having bosses projecting from opposite sides thereof,

wherein means are provided for securing said collars to said base, wherein the guide members are parallel laterally aligned rods slidably guided in said bosses, wherein the yokes extend across said rods and are rigidly mounted thereon and the blades have boss members spaced laterally therefrom, mounted on said rods, to move said blades into released positions as said yokes are cammed by spreading movement of the forks of the fork lift.

11. The removable container of claim 8, including first and second aligned socket members carried on said base on opposite sides of each fork opening, said socket members each having vertically extending socket portions registerable with aligned locating and locking members projecting upwardly from the flat bed of the vehicle, wherein latch dogs are slidably guided in each of said socket members and are biased into the open socket portions of said socket members, wherein means are provided for connecting said latch dogs together, and wherein a single fork in each fork opening is effective to simultaneously move said latch dogs on opposite sides of the fork opening into release positions, upon spreading movement thereof.

12. The removable container of claim 11, wherein the operative connection from the yoke to one latch dog includes parallel spaced rods guided for movement longitudinally of the container and forming a mounting means at one end for a yoke and a mounting means at their opposite ends for a latch dog, and

wherein spring means encircling said rods bias said latch dogs into release positions, wherein the operative connection to the latch dog guided in the first socket member to the latch dog guided in the second socket member is in the form of a channel having a base, one flange defined by said yoke and an opposite parallel flange spaced from said one flange a distance sufficient to accommodate the fork of a fork lift to pass therethrough,

and wherein the latch dog slidably guided in the second socket member is mounted on and extends from said opposite parallel flange to move in unison with said first mentioned latch dog.
